UNITED STATES PATENT OFFICE.

HARRY E. ASBURY, OF MELROSE PARK, PENNSYLVANIA, ASSIGNOR TO THE ENTERPRISE MANUFACTURING COMPANY OF PENNSYLVANIA, OF PHILADELPHIA, PENNSYLVANIA, A CORPORATION OF PENNSYLVANIA.

RELEASE CLUTCH FOR GRINDING MILLS.

Application filed July 1, 1924. Serial No. 723,563.

To all whom it may concern:

Be it known that I, HARRY E. ASBURY, a citizen of the United States, residing in Melrose Park, Montgomery County, Pennsylvania, have invented certain Improvements in Release Clutches for Grinding Mills, of which the following is a specification.

My invention relates to certain improvements in grinding mills, in which there is a stationary disk and a movable disk mounted on a rotating shaft.

The object of my invention is to provide a clutch, through which motion is imparted to the movable disk from the shaft, the clutch being so constructed that it will yield when foreign matter passes between the two disks, or when the mill is choked. This yielding prevents breaking of the parts.

In the accompanying drawings:

Fig. 1 is a longitudinal sectional view of a portion of a grinding mill illustrating my invention;

Fig. 2 is a sectional view on the line 2—2, Fig. 1;

Fig. 3 is a sectional view on the line 3—3, Fig. 1; and

Fig. 4 is a detached perspective view showing portions of the clutch.

Referring to the drawings, 1 is the body of the mill. 2 is a portion of an electric motor, having a shaft 3, which drives the shaft 4 of the mill. The coupling is made as shown clearly in Fig. 1. Enclosing the coupling is a sleeve 5. Between the head 6 of the sleeve and the end of a feed screw 7 is a coiled spring 8. This spring tends to force the two disks of the mill apart. The hopper 9 of the mill is directly above the feed screw 7. The discharge opening 10 for the ground material is located under the disks. The grinding disk 11 is secured to the body of the mill and has grinding teeth of any shape desired. The mill is fed by the screw 7 through the throat 12 of the disk. The rotating grinding disk 13 is mounted on an extension 14 of the feed screw 7.

Back of the grinding disk 13 is a disk 15. The two disks are secured to the screw 7 by one, or more screws 7a. On the shaft 4, beyond the screw 7, is a collar 16, which is secured to the shaft by a pin 17. This

collar has a transverse groove 18 therein, 55 as shown clearly in Fig. 4, and forms one member of the clutch. The other member of the clutch consists of a ball 19, which is mounted in a radial channel 20 in a projection 21 that is cast integral with the disk 60 15. The projection 21 is tubular, as shown. Mounted in the projection is a sliding plunger 22, back of which is a coiled spring 23, which is held in place by a screw 24. 65 The end of the plunger is beveled, as shown clearly in Fig. 4, and has a conical seat 25 at the center to receive the ball 19, when it is forced out of the groove 18 in the collar 16. This construction forms a release clutch between the power driven shaft and the grinding disk so as to prevent the breaking of the parts when the mill becomes choked.

Mounted on the body portion 1 is the cover plate 26. In this cover plate is a bearing 27, which is held in place by a set screw 28. Beyond the bearing and within an extension 29 of the cover plate 26 is a cam disk 30, which has three cam faces, in the present instance. These cam faces rest 75 80 against a cam block 31 that is secured to a sleeve 32 by means of screws 33, Fig. 1. This sleeve is mounted on the extension 29 of the cover plate 26 and is so shaped that it can be grasped by the hand to turn it 85 on the extension to adjust the cam block 31 in respect to the cam disk 30. Located in the cam disk 30 is a ball thrust bearing 34, which receives the thrust of the shaft 4. On the cam disk 30 is a projection 35, 90 which enters a recess in the bearing 27, which prevents the turning of the cam disk.

In order to hold the sleeve 32 in the position in which it is adjusted, a plunger 36 is 95 provided, which is mounted in the sleeve. Back of the plunger is a spring 37. This plunger is adapted to enter any one of the depressions 38 in the end of the cover plate 26, thereby retaining the sleeve in the position in which it is adjusted. In order to limit the movement of the sleeve, a pin 39, carried by the sleeve, extends into a slot 40 in the end of the extension 29 of the cover plate 26. The sleeve may have marks indicating whether it is adjusted to grind 100 "coarse," "medium" or "fine."

On the disk 15 are blades 41, which act to

clear the material from the interior of the grinding chamber. Opposite the projection 21 is a projection 42, which acts as a bearing, with the projection 21, to hold the disk 15 in alignment with the cover plate 26.

By the construction hereinbefore described, it will be seen that if the material should clog the grinding mill, or, if any foreign matter passes between the plates, the ball of the release clutch is forced out of the groove 18 and into the radial channel 20 in the projection 21, being held in the channel by the plunger 22, as shown by dotted lines in Fig. 2.

It will be noticed that the walls of the groove 18 are beveled. The bevel may be of any degree desired to allow the ball to be held in position until forced out, should the parts become clogged. Under ordinary grinding, the rotating grinding disk 13 is driven from the shaft 4 through the release clutch.

I claim:

1. The combination in a release clutch,

of a shaft; a collar on the shaft, said collar having a groove therein; a member on the shaft and having a tubular projection; a radial channel in the projection; a sliding plunger in the tubular projection; a spring back of the plunger; and a ball in the radial channel arranged to enter the groove in the collar, the plunger yieldingly holding the ball in engagement with the collar.

2. The combination in a release clutch, of a shaft; a collar thereon having a transverse groove therein, said groove having tapered walls; a member on the shaft and having a tubular projection thereon, said projection having a radial channel; a ball in the channel; a plunger in the tubular portion of the projection having a tapered end tending to hold the ball in the groove of the collar, said plunger having a conical seat in its end for the ball when moved out of engagement with the sleeve; and a spring back of the plunger.

HARRY E. ASBURY.
